CLAIM

The ornamental design for a feeder as shown and described.

DESCRIPTION

FIG. 1 is a top perspective view of a feeder in accordance with our new design;

FIG. 2 is a bottom perspective view of the feeder of FIG. 1; FIG. 3 is a top view of the feeder of FIG. 1;

FIG. 4 is a bottom view of the feeder of FIG. 1;

FIG. 5 is a right side view of the feeder of FIG. 1;

FIG. 6 is a left side view of the feeder of FIG. 1;

FIG. 7 is a front view of the feeder of FIG. 1;

FIG. 8 is a rear view of the feeder of FIG. 1; and,

FIG. 9 is an exploded top perspective view of the feeder of FIG. 1.

The broken lines in the drawings illustrate portions of the feeder that form no part of the claimed design.
